[57] CLAIM

The ornamental design for an athletic shoe sole, as shown and described.

DESCRIPTION

FIG. 1 is a right side elevational view of an athletic shoe sole showing my new design, the left side being substantially a mirror image thereto;

FIG. 2 is a bottom plan view thereof;

FIG. 3 is a cross-sectional view thereof as taken from line 3—3 in FIG. 2.

The broken line showing of an athletic shoe in FIG. 1 is environmental only and forms no part of the claimed design.
